Attorney.

UNITED STATES PATENT OFFICE.

WILLIAM F. LONG, OF GRAND HAVEN, MICHIGAN, ASSIGNOR TO PEERLESS NOVELTY COMPANY, OF GRAND HAVEN, MICHIGAN, A CORPORATION OF MICHIGAN.

ELECTRIC HEATER.

Application filed May 11, 1925. Serial No. 29,312.

This invention relates to an electric heating element which may be used in many places, such as in a device for heating curling or waving irons, electric toasters, small electric stoves and the like. The primary object and purpose of the present invention is to provide a particularly effective electric heating element, one which can be made economically and which, if any portion of it needs repair, can be readily reached for repair and the repairs easily made. In general the object of the invention is to simplify and make more effective electric heating elements of this character.

For an understanding of the invention reference may be had to the following description taken in connection with the accompanying drawing, in which,

Fig. 1 is a perspective view of the core of an electric heating element before the resistance coil is applied thereto.

Fig. 2 is a diagrammatic perspective view of the resistance coil in the form it takes when applied to the core, and

Fig. 3 is a horizontal section through the core shown in Fig. 1, the section being taken with the core inverted from the position shown in Fig. 1 and looking downwardly.

Like reference characters refer to like parts in the different figures of the drawing.

The core of the heating element is rectangular in cross section and includes spaced apart vertical sides 1 integrally connected by upper and lower horizontal sides 2, there being a continuous rectangular shaped opening 3 extending into the core nearly the full length thereof or until stopped by the partition 1^a formed integral with said core.

This core is of any suitable insulating material, such as porcelain, and is integrally formed in one piece. At one end portions of the core are cut away to make the concaved recesses 4 in the sides 1, as shown, and

against this end of the core a metal plate 5 is located, being permanently secured thereto by means of suitable angle brackets 6 which are attached to the core and plate by any fastening means such as small bolts or screws.

The plate 6 carries two binding posts 7 at the inner or core side thereof from which contacts 8 extend outwardly through the core for the detachable connection of an electric cord used to make connection between electric devices of this character and

a lamp or wall socket associated with a source of electric current supply.

In the outer vertical sides 1 of the core spaced apart vertical grooves 9 are made and separated by the ribs 10 which are left when the grooves are cut. The sides of the core are slotted through at the bottom of the grooves 9 between the ends of said grooves as indicated at 11. The vertical rib 10^a, shown in Fig. 1, on one side of the core and at the inner end thereof terminates short of the upper side of the core and is formed with a slightly under cut end as indicated at 12, the purpose of which will later appear. The upper and lower 70 sides of the core are likewise formed with ribs 13 lying between grooves or slots 14 but said ribs and slots extend diagonally across the core so that they join vertical ribs at opposite sides of the core not in the same 75 vertical plane. The upper and lower sides 2 are likewise slotted through making shorter slots 15, as best shown in Fig. 3. The end grooves 14 at the outer end of the core are continued as grooves 16 made at an angle 80 to the vertical in the sides 1 of the core in the direction of the binding posts 7, one of said slots being shown in Fig. 1.

The resistance wire of any well known form is applied to the core, a section 17 thereof lying in the slot or groove 16 and at its end being formed with a hook or loop 18 so as to readily engage with one of the binding posts 7. This wire is then carried through a groove 14 and thence downwardly 90 through a vertical groove 9 across through a lower groove 14 and thence upwardly in a vertical groove 9 at the opposite side of the core making the horizontal sections 19 and the vertical sections 20 of the resistance 95 coil as shown in Fig. 2, this being continued until the upper end of the rib 10^a is reached whereupon the resistance wire is turned around the upper end of said rib 10^a and under the overhang 12 and continued back 100 in vertical and horizontal sections 22 and 23, respectively, in the grooves 9 and 14 until the outer end of the core is reached whereupon the wire is laid, in an upwardly and inwardly inclined section 24, in the slot 16 105 in the opposite side of the core and terminates in a hoop 25 which is attached to the opposite binding post 7.

This completes the electric heating element which may be placed in any suitable casing 110

or housing dependent upon the purpose for which it is to be used.

The heating element thus made, it is apparent, inherently in its construction holds the parts of the resistance coil of wire from any short circuiting or contact with each other, the ribs 10 and 13 of insulating material completely separating and insulating the various sections of the coil from each other, the wire being located in the grooves 9 and 14 below the outer surface of said ribs 10 and 13. It is not necessary to cover this core with any insulating material nor in any way further protect various sections of the coil from each other. It is evident that with this construction the repair or replacement of the coil is exceptionally easy and it is also evident that its application to the core in the first instance is very simply and readily performed. The slots 11 and 15 permit the conduction of heat given off from the resistance coil to the opening 3 of the core in which articles which are to be heated may be inserted. This core is particularly practical and effective and has been used in connection with heating curling or waving irons which are placed lengthwise of the core within the opening 3. It is however apparent that the construction is not limited to this one use but may be utilized in a great many other places and relations. Accordingly the invention is to be considered, not as limited in use to any specific article, but as comprehensive of all forms of structure which come within the scope of the appended claims defining the invention.

I claim:

1. An electric heating element comprising an elongated core of rectangular cross

section formed at its vertical sides with vertical spaced apart ribs with grooves between the ribs and grooves joining the ribs and grooves of the vertical sides of the core, one of the vertical ribs at one end of the core terminating short of the adjacent side of the core, a resistance coil doubled around the end of said last mentioned rib and wound in the grooves in the outer side of the core, the various sections of the resistance coil lying alongside each other being separated and insulated from each other by said ribs, a plate attached to the end of the core farthest distant from the said shortened vertical rib, and binding posts carried by said plate to which the ends of the resistance coil are attached, substantially as described.

2. An electric heating element comprising a core of insulating material formed with a series of grooves and ribs around the same from one end to the other, said grooves and ribs being helically positioned and forming double threaded helical grooves and ribs around and lengthwise of the core, one of the end ribs in a side of the core being shortened at one end, a resistance coil doubled around said shortened end of said rib and wound around the core in the grooves thereof back toward the opposite end of the core, said core at said opposite end being formed with recesses in opposite sides thereof, a plate attached to said end of the core and binding posts carried by said plate to which the ends of the resistance coil are secured, substantially as described.

In testimony whereof I affix my signature.

WILLIAM F. LONG.
